UNITED STATES PATENT OFFICE.

HERBERT H. SCHMITT, OF PORTLAND, OREGON.

INSTRUMENT-SHARPENING MACHINE.

Application filed October 25, 1924. Serial No. 745,837.

This invention relates to devices for holding instruments for sharpening and pertains particularly to a device adapted especially for the sharpening of dental and surgical instruments.

The primary object of the invention is the provision, in a manner as hereinafter set forth, of an instrument holding device designed particularly for the sharpening of dental and surgical instruments and having means whereby an instrument can be rigidly held to sharpen and bevel, at any desired angle, the cutting edge thereof.

Another object of the invention is the provision, in a manner as hereinafter set forth, of an instrument holding device adapted to give to an instrument a cutting edge of any desired bevel, and having means whereby a number of instruments of the same kind may be inserted and removed from the device without changing the adjustment thereof, thereby providing each of the instruments with a cutting blade of exactly the same bevel.

Still another object of the invention is the provision, in a manner as hereinafter set forth, of an instrument holding device for giving to cutting instruments, an edge of any desired bevel, and having means whereby the liability of a round edge being formed upon the instrument is entirely eliminated.

Still another object of the invention is the provision, in a manner as hereinafter set forth, of a cutting instrument beveling device having means associated therewith by which the device may be trued up with respect to the surface upon which it is operated to give a perfectly beveled and true cutting edge to the instrument being sharpened.

A further and final object of the invention is the provision, in a manner as herein-after to be set forth, of a sharpener for giving to cutting instruments bevelled edges of any desired angle, which is easily and quickly set up, capable of fine and accurate adjustment, simple in operation, of neat appearance, strong, durable, and inexpensive to manufacture.

The invention will be best understood from a consideration of the following detailed description taken in connection with the accompanying drawings, forming a part of this specification, with the understanding that the invention is not confined to any

strict conformity with the showing of the drawings, but may be changed and modified so long as such changes and modifications mark no material departure from the salient features of the invention as expressed in the appended claims.

In the drawings, Figure 1 is a side elevation of the device embodying this invention, shown in the position in which it is used, a portion thereof being removed before the machine is set in operation.

Figure 2 is a top plan view of the device as in use.

Figure 3 is a section taken upon the line 3—3 of Figure 2.

Figure 4 is a section upon the line 4—4 of Figure 1.

Figure 5 is a section through the basal portion of the device.

Figure 6 is a plan view of a supporting structure used in connection with the device.

Figure 7 is a detail view of the indicator dial of the device, and

Figure 8 is a plan view of a pointer member used in connection with the dial.

Referring now to the drawings in detail wherein like numerals of reference indicate corresponding parts throughout the several views, the device embodying this invention comprises two distinct but inter-dependent structures, namely an instrument carrying structure indicated as a whole by the numeral 1, and a parallelogram, indicated generally by the numeral 2.

The instrument carrying structure 1 comprises a base portion of inverted substantially U-shaped conformation, as indicated at 3, and the terminal ends of the arms of this structure 3 are spherical, as indicated at 4, to provide supporting feet. The central portion or apex of the base 1 is formed to provide the vertically positioned centrally apertured collar 5 having the transversely extending threaded passage 6 extending through one side and opening into the longitudinal bore therethrough to receive a thumb nut 7.

Cooperating with the base structure 3 is a connecting rod structure comprising a long arm 8 and a right angularly extending short arm 9, which short arm 9 is adapted to extend through the bore in the collar 5 and is secured in this bore by means of the thumb nut 7. The forward or terminal end of the long arm 8 of the connecting rod member is flattened upon one side as indicated at 10,

and against this flattened surface there is secured a semi-circular calibrated dial 11. This dial is secured in position by means of the rivets 12 which extend therethrough and through the end of the arm 8. As shown, this dial 11, which comprises a semi-circular disc, has a slight extension downwardly along its base portion, as at 13, and the radial center of the dial is provided with an aperture 14, which aperture is positioned upon the longitudinal center of the arm 8 and coincides with an aperture 15 formed through the end of the arm. The extension 13 of the dial allows the same to be so positioned that the aperture 14 may be formed upon the radial center thereof.

The outer end of the arm 8 carries an instrument holder, indicated generally by the numeral 16, and this holder comprises a head 17 and a threaded longitudinally extending reduced portion 18, which portion extends through the aperture 14 in the plate 11 and the aperture 15 in the end of the arm 8 and carries upon its outer end a wing nut 19, which bears against the arm 8 to hold the instrument holder in a position at right angles to the end of the arm 8, as shown clearly in Figures 2 and 3. Upon the face of the shoulder formed between the head 17 and reduced portion 18, there is formed a pair of pin members 20, which pins engage in apertures 21 of a collar 22 which collar has a central aperture 23 traversed by the reduced portion 18 and carries thereon a pointer 24. This collar and pointer bear against the face of the dial 11 to indicate the desired angle at which the instrument is to be bevelled, as will be explained hereafter.

The head 17 has formed therethrough at right angles to the longitudinal center thereof of an instrument receiving aperture 25, and the longitudinal axis of the pointer 24, when in position between the head 17 and the face of the dial 11, is parallel with the longitudinal axis of this passage 25 through the head, thus, when an instrument 26 is in position in the aperture 25, the longitudinal axis of the handle of the instrument will be parallel with the longitudinal axis of the pointer 24 and consequently when the head and pointer is revolved to indicate any one of the numerous calibrations upon the disc 11, the instrument will assume the angle indicated by the pointer upon the dial with respect to the arm 8 and the surface upon which the machine is supported.

In order to hold the instrument 26 rigidly in position in the aperture 25 to prevent any play therein, a cap 27 is provided which slips over the outer end of the head 17, as shown in Figure 3, and the inner edge of this cap is provided with the diametrically oppositely positioned notches 27' which engage over the handle of the instrument, as shown in Figure 1 and a tightening screw 28, having

a reduced threaded portion 29 extending through the outer end of the cap 27 and engaging in the end of the head 17, serves to draw the cap in over the head and forces the instrument 26 tightly against the wall of the passage 25, thereby holding the same rigidly in position.

The parallelometer, indicated generally by the numeral 2, is not a permanent part of the device itself, that is, it is not attached to the machine when operating the same to sharpen an instrument. Its primary function is to support the longer arm 8 of the connecting rod so as to maintain it in a parallel position while the instrument 26 is being adjusted to position its blade at the proper angle upon the stone 30 upon which it is sharpened.

The parallelometer comprises a base portion 31 of cone shape, as shown, and there extends from the apex of this base a vertical standard 32.

The standard 32 supports a supporting paralleling device, which comprises a central vertical short post member 33 which has extending therethrough an eccentrically positioned aperture 34. This aperture extends longitudinally of the post, as shown in Figure 6. A threaded bore 35 is formed in the post which opens into the aperture 34 and into this bore a binding screw 36 is threaded to engage the post 32 and support the paralleling device in position.

Extending from the lower portion of the post 33 is a pair of upwardly curving arms 37 which, as shown in Figure 1, merge at their base to provide an upwardly curving arcuate member, and the upper end of each of these arms is finished off square and has cut in the edge thereof a semi-circular recess 38. As shown in Figure 6, the arms 37 taper toward their upper ends, and they are adapted to receive across their ends in the recesses 38 the long arm 8 of the instrument supporting portion of the machine. These arms, as will be readily seen, may be raised or lowered on the upright rod and fixed at any desired point by means of the thumb set screw 36 and due to the eccentrically positioning of the aperture 34, the standard 32 will not be in the way of the arm 8 when it is extending across the ends of the arms 37.

The operation of the device is as follows.

The parallelometer is placed in position upon the surface on which the device is to be used, preferably a glass surface and the instrument carrying structure 1 is positioned with the long arm 8 resting across the ends of the arms 37 of the parallelometer and in the recesses 38. The thumb screw 7 is then loosened to allow the arm 9 to slide freely through the head 5 of the base portion and the thumb screw 36 is also loosened to allow the post 33 to slide freely upon the standard 32 to raise or lower the connecting rod to 130

the desired height. When the connecting rod has been positioned as desired, the thumb nut 36 is tightened against the standard 32 and the thumb nut 7 is then 5 tightened against the short arm 9 of the instrument holding structure firmly securing the base 3 in position with the feet 4 upon the surface upon which the device is to work and holding the arm 8 parallel with the 10 working surface.

The wing nut 19 is now loosened on the reduced extension 18 of the instrument holder 16, and the instrument holder is 15 revolved carrying with it the pointer 24 to set the pointer in a position directed toward any one of the calibrations upon the dial 11. When the pointer has thus been turned in the proper position, setting the passage 25 at the proper angle, the thumb nut 28 is 20 loosened and the handle of the instrument to be sharpened is inserted through the passage 25 until the blade thereof rests upon the sharpening stone 30. When in this position the thumb nut 28 is then tightened drawing 25 the cap 27 in upon the head 16 until it engages the instrument 26 and firmly clamps the same in position in the aperture 25. The instrument will now be held at the proper angle to give a bevel of a degree corresponding to the degree indicated by the pointer 30 24 upon the dial 11. The paralleloometer 2 is now removed from beneath the arm 8, and the device is ready for operation, the base 3 serving to support the rear part of the device and the instrument 26 acting as a third leg to support the forward portion of the device. The device is then grasped at the bend of the connecting rod with the palm of the hand resting upon the base portion and 40 is given the proper movement across the supporting surface to move the blade of the instrument 26 across the grinding stone 30. Any desired amount of pressure can be 45 brought to bear upon the instrument by the hand which is guiding the machine back and forth, and owing to the manner in which the legs or feet 4 of the base member 3 are positioned, it will be impossible for there to be any side motion or swinging of the 50 machine to form a round edge upon the instrument, for the blade thereof is held perfectly flat upon the stone 30 at all times during the operation.

If more than one instrument of the same type is to be sharpened and each one is to 55 have a bevel of exactly the same degree, it is only necessary to saddle the arm 8 upon the paralleloometer, so it will be held at the same height and then loosen the thumb nut 28 and remove one instrument for the insertion of the other, without changing the adjustment of the head and pointer upon the dial 11, thereby allowing any number of instruments to be sharpened with a blade bevelled at the same angle. 60 65

From the foregoing description it may be seen that a neat and novel device is provided for the sharpening of bevel bladed instruments which will give quick and accurate 70 results.

Having thus described my invention what I claim is:

1. The combination, in a device of the character set forth, of a tool holder comprising a relatively long arm and a short arm extending at right angles from one end thereof, a base adapted to adjustably receive said short arm, means upon the free end of said long arm for adjustably holding an instrument to be sharpened, and vertically 75 adjustable means adapted to temporarily maintain the long arm in horizontal relation to the supporting surface for said base, while a tool and the base are fixed in position. 80 85

2. The combination, in a device of the character set forth, of a tool holder comprising a relatively long arm and a short arm extending at right angles from one end thereof, a base adapted to adjustably receive said short arm, means upon the free end of said long arm for adjustably holding an instrument to be sharpened, and means adapted to temporarily maintain the arm in horizontal relation to the base supporting 90 95 surface, comprising a standard, a vertically adjustable member carried thereby, and an arcuate member carried by said adjustable member, having the ends directed upwardly and provided with recesses to receive said 100 long arm adjacent each end thereof, as and for the purpose set forth.

In testimony whereof, I affix my signature hereto.

HERBERT H. SCHMITT.
